AIR CONDITIONING APPARATUS

Keith T. Davis, Milwaukee, Wis., assignor to
 L. J. Mueller Furnace Company, Milwaukee,
 Wis., a corporation of Wisconsin

Application December 14, 1942, Serial No. 468,913

7 Claims. (Cl. 98—33)

This invention relates to improvements in air conditioning apparatus, and more particularly to a system for buildings or enclosures, of a reversible character susceptible of being operated for heating purposes in the winter and for summer comfort conditioning.

A general object of the invention is to provide an apparatus arranged for conventional forced circulation warm air winter heating, together with a novel arrangement of ducts and dampers which permits the forced circulation of cool or conditioned air through the building, in summer.

A further object of the invention is to provide a building air conditioning apparatus of the character described which, during summer comfort conditioning, utilizes both the supply ducts to the building rooms and the normal return ducts for discharging into the rooms cooled or conditioned air.

A further object of the invention is to provide an air conditioning apparatus which, for summer operation, draws a supply of relatively cool air into the fan or blower casing through interposed filters or air treating mechanism so that the air is influenced thereby before being introduced into the building rooms.

A further object of the invention is to provide an air conditioning apparatus which, for summer cooling, actually functions to push filtered and conditioned air into the building rooms with the spent air being ultimately evacuated through open windows in rooms where a marked circulation is desired.

A further object of the invention is to provide an air conditioning apparatus which, when used for summer comfort conditioning in localities having low relative humidities, may employ an evaporative cooler to condition the air prior to the forcing of the same into the building rooms.

A further object of the invention is to provide an air conditioning apparatus which may include an evaporative cooler without any increase in the size of the ducts utilized by the apparatus when it functions as a heating apparatus.

A further object of the invention is to provide an air conditioning apparatus operable for summer comfort conditioning which exhausts air through a building window and replaces the air with cool outdoor night air which is first filtered to remove disagreeable dust and hay-fever irritants.

A further object of the invention is to provide an air conditioning apparatus primarily adapted for a home or building installation, but also applicable to commercial or industrial usages where in the air in an enclosure should, because of industrial operations therein, be susceptible of having its characteristics and temperature quickly changed.

A further object of the invention is to provide

a dual purpose air conditioning apparatus which is of very simple construction, which may be easily changed over from heating to cooling duties by simple manipulations, which is efficient in operation, and which is well adapted for the purposes described.

With the above and other objects in view, the invention consists of the improved air conditioning apparatus and its parts and combinations as set forth in the claims, and all equivalents thereof.

In the accompanying drawings, in which the same reference characters indicate the same parts in all of the views:

Fig. 1 is a semi-schematic, fragmentary vertical sectional view through the lower portion of a building equipped with the improved air conditioning apparatus;

Fig. 2 is a vertical sectional view through the air conditioning apparatus, as adjusted for summer use;

Fig. 3 is a plan view of the showing in Fig. 2, and

Fig. 4 is a vertical sectional view of a modified form of the apparatus, incorporating an evaporative cooler, and as arranged for summer use.

Referring now more particularly to the drawings, it will appear that in Fig. 1 the invention, by way of illustration, has been shown as installed in the basement of a small dwelling. The building or dwelling includes exterior walls 8, partitions 9, windows 10 in the several rooms, and a door 11. The walls are supported by a foundation 12 defining a basement or cellar 13 which is separated from the dwelling rooms thereabove by a horizontal floor 7. The basement 13 accommodates the improved dual purpose air conditioning apparatus, designated generally by the numeral 14, which is used both for heating in winter and for cooling or conditioning the air in summer.

The apparatus 14 is shown most clearly in Fig. 2, and for winter functioning it is of the type which circulates by a blower or a fan heated air. The heating unit 15 is, by way of illustration, a coal-fired hot air furnace, but it should be understood that within the contemplation of the invention the apparatus 15 may be fired by oil, gas, or any of the other conventional fuels. Also, steam or hot water heat exchanger coils could be used for the same purpose.

The heating apparatus 15 includes an inner pot member 16 spacedly surrounded by a casing 17 in which, for winter purposes the air to be heated circulates and rises, ultimately passing into a top plenum or outlet chamber 18. Opening out of the plenum chamber 18 are air-supply or distributing ducts 19 which terminate at registers 20 in the several rooms of the building to be heated.

Directly associated with the heating apparatus

17 is a blower or fan casing 21 which, in its lower portion, houses a conventional motor operated blower 22. A chamber 23 surmounts the blower casing 21, and therebelow, in the form of the invention illustrated in Fig. 2, are filter screens 24. A main trunk duct 25, which for winter heating purposes functions as the cold air return duct for the apparatus, opens into an auxiliary chamber formed in the upper portion of the chamber 23 by an interposed damper 32. This main trunk duct has connected to it the ends 10 of return air ducts 26 which lead away from return air registers 27 located in the base portions of the dwelling rooms. This duct work may be termed "auxiliary duct work." That portion of the casing 21-23 which is above a damper 32 constitutes the auxiliary chamber, while the portion of the casing below said damper constitutes the fan chamber.

An inlet air duct 28, for summer usage, opens 20 into the casing 21-23 above the filters 24 and below the damper 32. The last mentioned duct 28 may either extend to exteriorly of the building, or it may terminate within the building basement, it being optional and dependent upon the 25 best source of cool air in the summertime. There is also a duct 29 constituting a direct connection or by-pass between the heating apparatus plenum chamber 18 and the auxiliary chamber in the upper portion of member 23. Likewise, at the lower portion of the blower casing 21 there is a duct or connection 30 extending between the discharge or outlet side of the blower 22 and the air space within the heating apparatus casing 17. Flow of air through the upper connection 29 is controlled by a manually operated damper 31. As mentioned, the damper 32 separates the auxiliary chamber in the upper portion of member 23 from the base or fan chamber 21, the last mentioned damper being disposed above the discharge end of the cool air inlet duct 28 and below the openings of the ducts 25 and 29 respectively. Within the cool air inlet duct 28 there is a third damper 33. The dampers 31, 32, and 33 are of conventional construction and will not be described in detail. Suffice it to say that each damper is composed of a plurality of pivotal louvers having a link connection with one another and with an operating rod and lever extending exteriorly of the duct or chamber in which the damper is installed, so that each damper may be manually moved from open to closed position, or vice versa.

The improved air conditioning apparatus is adapted to function in its customary manner in the wintertime for heating purposes. Fuel is burned within the pot 16 of the unit 15, and the blower 22, within the casing 21, is operated in the customary manner. It should be specifically noted that for winter operation the dampers 31, 32, and 33 are adjusted in a manner opposite to that illustrated in Fig. 2. The dampers should be set so that damper 31 is closed, damper 32 is open, and damper 33 is partially or completely closed. The air to be heated circulates in the space between the pot 16 and the casing 17, rising into the heating apparatus plenum chamber 18, and being discharged into the air supply ducts 19. The latter connect with the warm air registers 20 in the rooms of the building and discharge heated air into the rooms. As room air cools it drops and returns to the apparatus 14 by entering the return air registers 27 from whence the air is drawn through the return air ducts 26 into the auxiliary chamber 23. The fan

5 or blower 22 induces the desired circulation, and due to the settings of the various dampers the return cool air is drawn through the filters 24 or other conditioning medium and is subsequently discharged by the blower through the connection 30 into the lower portion of the heating apparatus casing 17 for re-heating and re-circulation.

For summer usage the heating apparatus is not fired. The dampers 31, 32, and 33 are arranged in the manner shown in Fig. 2 with the damper 31 open, the damper 32 closed, and the damper 33 open. Through this arrangement of dampers it will be noted that the auxiliary chamber, into which the return air ducts open, is directly connected with the plenum chamber 18 of the apparatus 15. The aforesaid auxiliary chamber is shut off from the fan chamber and is furthermore shut off from the summer inlet air duct 28, which now opens into the fan chamber above the filters or conditioning unit. Operation of the blower 22 causes relatively cool air to be drawn into the upper portion of the casing 21 through the summer air inlet duct 28. The latter obtains its air supply from the basement of the building or from the outside, depending upon which provides the best source of cool air. This supply of cool air, after being drawn through the filters or conditioning unit 24, is blown into the 30 space of the apparatus 15 between the casing and pot, and then passes into and through the various supply ducts 19 and the ducts 25 (which for winter purposes are return air ducts). It is one of the particular features of the invention 35 that for summer conditioning air is supplied to the rooms of the building not only through the normal supply ducts 19, but also through the ducts 25, whereby the number of available air supply ducts is increased and air is discharged into the rooms of the dwelling through both the registers 20 and 27. Cool and filtered air is thus discharged into the house in very ample quantities. If a marked circulation is desirable in any 40 of the rooms, one or more of the windows 10 may be opened, through which the undesirable room air may be purged.

A slightly modified form of the invention is illustrated in Fig. 4 wherein the heating apparatus 15' is the same as that illustrated in connection with the principal form of the invention. However, in lieu of the blower and filter casing 21 of Fig. 2, there is, in the modification, a casing 21' which houses a conventional form of evaporative cooler.

55 The inlet side of the evaporative cooler casing 21' is covered by a screen 40 and carries an extension 41, the major portion of which may be considered as a part of the cooler or fan casing 21'. Opening into the top of the extension 41 are one or more return air pipes 25' which, as in the principal form of the invention, extend to return air registers in the lower portions of rooms in the building. The upper auxiliary chamber portion of the extension casing 41 is furthermore in direct communication with the plenum chamber 18' of the heating apparatus 15' by a duct or conduit 29' having one end thereof controlled by a damper 31'. Within the upper portion of the extension 41 and slightly below the open ends of the ducts 25' and 29' and defining the auxiliary chamber there is a damper 32'. Opening into the extension 41 below the damper 32' is a cool air inlet duct 28', used 60 when the apparatus is operated in the summer-

time, and having its discharge end controlled by a damper 33'.

Relatively dry air, during summer operation of the apparatus, passes from the air inlet duct 28' into the extension 41, through the screen 40, and into the evaporative cooler casing 21. There the air is treated by a water spraying apparatus 42 and is subsequently drawn through a moistened filter pad. Within the other side of the evaporative cooler 21' is a blower 22' which forcefully discharges the cleansed, cooled and water-treated air into the space between the heating apparatus pot 16' and its casing 17', it being noted that there is a connection 30' between the discharge end of the blower 22' and the interior of the furnace casing 15'. Subsequently the circulation of cooled and conditioned air is similar to that described in connection with the principal form of the invention, and said cooled and conditioned air passes through the ducts 25' as well as the normal ducts 19', entering the building rooms through the warm air registers and the return air registers. Obviously for summer operation the dampers 31', 32', and 33' are arranged as disclosed in Fig. 4. When the modified form of apparatus is used in winter for heating purposes, said dampers are reversed. The modified form of apparatus, for summer use, finds its greatest utility in localities where the relative humidity is generally low. Evaporative cooling ordinarily requires a substantial number of air changes per hour. If an evaporative cooler were to use only the normal duct work of a hot air heating apparatus, for proper operation the duct work would have to be of substantially larger cross-section than is ordinarily required for heating purposes, and it would obviously not be economical to make a heating apparatus over size to permit its use in summer for cooling purposes as during the heating season the same would produce substantial heat losses. These contingencies are nicely taken care of in the form of the invention illustrated in Fig. 4 because for cooling purposes the heating apparatus return air ducts serve with the normal hot air ducts for supplying cool and conditioned air to the building rooms. This, therefore, greatly increases the duct work capacity and adapts it for the evaporative cooler installation.

It is a recognized fact that successful operation of an evaporative cooler cannot be accomplished if conditioned air is recirculated because air passed through the evaporative cooler is subjected to a water spray and if an attempt were made to subsequently recirculate this air and pass it through the cooler it would not be "dry" air. The improvement of Fig. 4 eliminates this difficulty by introducing "new" air into the cooler during summer operation. In a conventional heating system, if an evaporative cooler were used in conjunction therewith, only half of the value of its duct work would be usable, inasmuch as return flow to the conditioning apparatus would be detrimental to successful operation because such return air would not be "dry" air, as above pointed out.

While the specification speaks of "cool" air in connection with operation during the summer cycle it is the intent that this term include air whose source may be only the basement of the building, or the outside, inasmuch as nighttime outdoor air is generally cooler than air within a building or enclosure. Hence the above-men-

tioned term should include fresh air, outside air, new air, or make-up air according to the implication of these terms in the air conditioning art.

For purposes of illustration the apparatus 14 has been shown and described as being installed in the basement of a building. The practice as to the location of installations of this general character differs in different localities, and according to the types of buildings or dwellings. Hence, it should be understood that where conditions make it advisable the apparatus 14 might be installed in the attic, closet, utility room, or porch of a building.

The term "building" as used herein is intended to include enclosures generally and a "room" might be a chambered portion of an enclosure. Conceivably the improved apparatus might be applied to commercial or industrial usages and operate to quickly change the characteristic and temperature of a chamber or room wherein operations were being performed on industrial products.

The improved air conditioning apparatus is economical and efficient and provides a dual system adapted for winter and summer conditioning. For summertime the new air from a selected source is filtered and conditioned before being passed into the rooms of the building, and it is a particular feature of the invention that when the apparatus is operated for cooling purposes the duct work which normally serves as conduits for return air then is added to the normally used air supply duct work and increases the duct work functioning for conditioned air supply purposes. The apparatus is easily manually changed over from one use to the other, is of simple and novel construction, and is well adapted for the purposes set forth.

What I claim is:

1. In combination, an enclosure having a chamber therein to be air conditioned, said enclosure also having associated therewith a forced warm air circulating system provided with separated inlet and outlet chambers and an intermediate air chamber therebetween and in direct communication with both of the aforesaid chambers, air distributing duct work between said outlet chamber and the enclosure chamber, secondary duct work between the enclosure chamber and said system inlet chamber, a by-pass connection between said system inlet and outlet chambers, a fan within said inlet chamber, an air supply duct opening into said inlet chamber, a damper controlling air flow through said duct, a damper controlling the by-pass connection between the outlet and inlet chambers, and a third damper within the inlet chamber controlling communication between the secondary duct work and the inlet chamber.

2. In combination, an enclosure having therein a forced warm air circulating system provided with separated fan and outlet chambers and an intermediate chamber therebetween and in direct communication with both of the aforesaid chambers, the fan chamber having an auxiliary chamber, air distributing duct work between said outlet chamber and a space in the enclosure, secondary duct work between a space in the enclosure and said auxiliary chamber, a direct connection between said outlet and auxiliary chambers, a controlled air supply duct opening into said fan chamber, a damper controlling the connection between the outlet and auxiliary chambers, and another damper controlling air

flow between the auxiliary chamber and the fan chamber.

3. In combination, a building having therein a forced warm air circulating system adapted to be fired only for winter operation and provided with separated fan and outlet chambers and an intermediate chamber therebetween and in direct communication with both of the aforesaid chambers, the fan chamber having an auxiliary chamber, air distributing duct work between said outlet chamber and a space in the building, secondary duct work between a space in the building and said auxiliary chamber, a direct connection between said outlet and auxiliary chambers forming communication between the outlet chamber and auxiliary duct work, a controlled air supply duct opening into said fan chamber, a damper controlling the connection between the outlet and auxiliary chambers which when open for summer operation causes the secondary duct work to augment the distributing duct work for the delivery of conditioned air in an outward direction to the building space and which when closed for winter operation carries return air in a reverse direction, and another damper controlling communication between the auxiliary and fan chambers adapted to be closed for summer operation of the system and open for winter operation of the system.

4. In combination, a building having therein a forced warm air circulating system including a hot air heating unit fired only for winter operation and an air conditioning unit, said air conditioning unit having a fan chamber and an auxiliary chamber, and the heating unit having a plenum chamber, the heating unit forming an intermediate chamber between the fan chamber and the plenum chamber and being in direct communication with both, air distributing duct work between said plenum chamber and a space in the building, secondary duct work between a space in the building and said auxiliary chamber, a direct connection between said plenum and auxiliary chambers, a controlled air supply duct opening into said fan chamber, a damper controlling the connection between the plenum and auxiliary chambers which when open for summer operation causes the secondary duct work to be directly connected with the distributing duct work to augment the latter for the outward delivery of conditioned air to the building space and which when closed for winter operation carries return air in a reverse direction to the auxiliary chamber, and another damper controlling communication between the auxiliary and fan chambers adapted to be closed for summer operation of the system and open for winter operation of the system.

5. In combination, a building having therein a forced warm air circulating system including a hot air heating unit fired only for winter operation and an air conditioning unit, said air conditioning unit having a fan chamber and an auxiliary chamber, and the heating unit having a plenum chamber, the heating unit being connected to and forming an intermediate chamber between the fan chamber and the plenum chamber, air distributing duct work between said plenum chamber and a space in the building, secondary duct work between a space in the building and said auxiliary chamber, a direct connection between said plenum and auxiliary chambers, an inlet duct for "new" air opening into said fan chamber, a damper controlling air

flow from said duct to the fan chamber, a damper controlling the connection between the plenum and auxiliary chambers which when open for summer operation causes the secondary duct

5 work to be connected with the distributing duct work to augment the latter for the outward delivery of conditioned air to the building space and which when closed for winter operation carries return air in a reverse direction to the auxiliary chamber, and another damper controlling communication between the auxiliary and fan chambers adapted to be closed for summer operation of the system and open for winter operation of the system.

15 6. In combination, a building having therein a forced warm air circulating unit fired only for winter operation and an air conditioning unit, said air conditioning unit having a chamber with a fan and an air treating device there adjacent,

20 the air conditioning unit also having an auxiliary chamber, the heating unit having a plenum chamber and also forming an intermediate chamber between and in communication with the fan chamber and the plenum chamber through which air is circulated from the air conditioning unit by the operation of the fan, air distributing duct work between said plenum chamber and a space in the building, secondary duct work between a space in the building and said auxiliary chamber, a direct connection between said plenum and auxiliary chambers, an inlet duct for "new" air communicating with the air treating device and fan chamber, a damper controlling air flow from said duct to the fan chamber, a damper controlling the connection between the plenum and auxiliary chambers which when open for summer operation causes the secondary duct work to be connected with the distributing duct work to augment the latter for the outward delivery of conditioned air to the building space and which when closed for winter operation carries return air in a reverse direction to the auxiliary chamber, and another damper controlling communication between the auxiliary and fan chambers adapted to be closed for summer operation of the system and open for winter operation of the system.
